UNITED STATES PATENT OFFICE.

JAMES G. HENDRICKSON, OF BAYONNE, NEW JERSEY, ASSIGNOR TO THE NEW YORK LABELLING MACHINE COMPANY, A CORPORATION OF NEW YORK.

LABELING-MACHINE.

SPECIFICATION forming part of Letters Patent No. 733,039, dated July 7, 1903.

Application filed March 29, 1902. Serial No. 100,519. (No model.)

To all whom it may concern:

Be it known that I, JAMES G. HENDRICKSON, a citizen of the United States, and a resident of Bayonne, in the county of Hudson and State of New Jersey, have invented certain new and useful Improvements in Labeling-Machines, of which the following is a specification, taken in connection with the accompanying drawings, which form a part of the same.

This invention relates to labeling-machines of the type shown in patent to Gilfillan and McKaig, No. 692,055, January 28, 1902, in which a series of articles are simultaneously and intermittently fed along the runway into coöperation with a series of intermittently-acting labeling devices mounted adjacent the runway.

In the accompanying drawings, in which the same reference character refers to similar parts in the several figures, Figure 1 is a side elevation of a labeling-machine embodying this invention. Fig. 2 is a plan view showing parts of the same. Figs. 3, 4, 5, 6, and 7 show details.

The rigid frame A is formed at the top of the same with the transverse pieces A' and A'', the latter being formed with an extended upper surface to serve as a receiving-table. The longitudinal guides B and C are adjustably secured to the transverse pieces by screws B' C', which coöperate with suitable slots, so that these guides may be adjusted to form a runway of any desired width. The guides are each provided with ledges B⁵ and C⁶, respectively, to support articles as they are fed along this runway. Upon the guide C are mounted a series of spring-guides C², which are secured in slots C³ in the guide C by screws C⁴. These spring-guides are intended to press upon articles in the runway to crowd them against the face of the opposite guide B, so as to hold them more accurately in alinement as they are fed along the runway. Above the runway and at the several stations along the same directly above the paster H⁹, the label-box L, and presser P there are mounted movable retainers, which firmly clamp articles down upon the runway while the labeling devices are acting upon

them. The retainer F, which may, if desired, be provided with a suitable face, of leather or other yielding material, is pivoted by the pivot F' to the sleeve F''. This sleeve is free to turn about the stud F³, but is held in position upon the stud by the thumb-nut F''. This thumb-nut engages the threaded end of the bolt F⁷ and serves to secure the stud in any desired position upon the slide F⁶, the bolt entering a suitable opening in this slide. The slide is mounted to move vertically in an opening F⁵, formed in the retainer-support F⁴, which is rigidly secured to the frame of the machine. This slide is reciprocated vertically through a suitable mechanism to be described, and the retainer is reciprocated with it, the connections for the retainer forming a universal joint with the slide and slot, permitting the retainer to be adjusted with respect to the slide. The pin F⁹ is secured to the slide, and the retainer-lever G, which is pivoted to move about the pin G' in the support, actuates the slide by the retainer-link G², pivoted by the pin G¹⁰ to the lever and engaging the pin F⁹, which passes through a suitable slot G⁸ in the link. The spring G⁴ acts between the link and the pin to press the slide yieldingly down upon articles in the runway. Each one of the retainer-levers is actuated in unison, since the retainer-bar G⁵ is pivoted to the upper end of each one of the retainer-levers. The retainer-arm N⁶, rigidly secured to the shaft N, operates the retainers through the connecting-bar G⁷, which is pivoted at its upper end to the pin G⁶ in one of the retainer-levers. Any desired form of connection may be employed between the retainer-arm and the connecting-bar to transmit the oscillations of the retainer-arm to the retainers. It is desirable, however, in order to have the retainers yieldingly clamp the articles upon the runway and to have them released as quickly as possible from engagement with these articles to provide a spring connection between these two parts and an automatic latch. This connection is illustrated in Fig. 3. The latch H is pivoted about the pivot N' in the end of the retainer-arm N⁶. The upper end of this latch H' is given a hook form to engage

the projection G^9 on the connecting-bar. The connecting-bar is formed at its lower end with a slot G^8 , through which the pin N^7 passes, so that a considerable freedom of movement is allowed between these two parts. The spring N^9 serves to press the connecting-bar upward, the proportion of the parts being such that as soon as the latch is released from the projection G^9 the spring N^9 throws the connecting-bar up sufficiently to quickly raise the retainers from contact with the articles in the runway. The spring N^8 bears against the latch and throws its upper end against the projection G^9 . The trip H^3 , pivoted to the frame adjacent the latch, is pressed forward by the light spring H^4 , so that as soon as the retainer-arm starts to move in an upward direction the trip engages the part H^2 of the latch and releases the upper end of the latch from the projection G^9 , thereby releasing the retainers. As the retainer-arm continues to move upward the slides reach the upper limit of their movement, and thereupon the pin N^7 in the retainer-arm moves up along the slot G^8 in the connecting-bar, extending the spring N^9 , so that the latch hooks over the projection G^9 , as is indicated in Fig. 3. On the downward movement of the retainer-arm the retainers are all moved into contact with articles upon the runway, the springs G^4 pressing each retainer down with substantially equal pressure in spite of any slight irregularities in the various articles. Then as soon as the retainer-arm moves upward the latch is released and all the retainers are at once disengaged.

The feeder (illustrated in Figs. 2 and 7) is in the form of a bar D of rectangular cross-section, which moves in a guideway in the guide B , so as to be supported throughout its whole length during its reciprocation. Suitable retaining-screws B^3 serve to hold it in position in connection with plates B^7 . A number of feeding-pawls D' are pivoted to the feeder by the pivots D^2 , suitable springs D^4 being employed to hold these feeding-pawls out into the runway, their position being determined by the pins D^8 , which engage the rear ends of these pawls. The connector E is secured to the feeder by the screws E^8 , which pass through suitable slots E^9 in the connector, so that the connector may be readily adjusted upon the feeder and rigidly secured thereto. The holding-pawls E' move about the pivots E^2 in the connector, the pivots E^3 serving to connect all of these holding-pawls to the actuator E^4 , which is reciprocated by suitable connections engaging the bolt E^5 in the actuator. The extent of movement of the holding-pawls is limited by the stop E^6 or pin in one of the holding-pawls, which, as indicated in Fig. 2, co-operates with a suitable opening formed in the connector to allow the holding-pawls to protrude into the runway to the desired extent. By forming the feeder in this manner it is firmly supported in the guide-

way and cannot swing outward under the pressure exerted by the holding-pawls. All of the articles are therefore engaged in a regular manner and fed forward accurately. 70

The gage B^2 is adjustably secured to the guide B by the bolts B^3 and extends around the ends of the same. In either end of this gage the gage-screws B^4 are provided, suitable lock ends being arranged to adjust these 75 gage-screws in position. The feeder in its reciprocation moves into engagement with the gage-screws at either end of its stroke, so that the extent of its reciprocation is limited by the distance between these gage-screws. 80 Since it is desirable that the feeder should accurately place articles in position at the several stations along the runway, it is desirable to regulate the forward position of the feeder, and this is readily done by bodily 85 moving the gage, which may be secured in any desired position by the screws B^3 .

It will be noted by reference to Fig. 2 that the plate A^3 is mounted at the rear end of the runway, its position being adjusted by 90 the screw A^4 , which engages a suitable slot in the plate. Articles as they are fed through the machine are placed in contact with this plate, and then the actuator moves the holding-pawls into engagement with each one of 95 the articles to hold them against the feeding-pawls. A further movement of the actuator reciprocates the feeder, carrying the articles forward one station, the final position of the articles being regulated by the position of 100 the gage-screw B^4 . As the actuator moves in a rearward direction, the feeding-pawls yield as they pass the articles in the runway, so as to move into position behind the several articles. 105

The paste apparatus, which comprises the paste-reservoir H^8 and the paster H^9 , is constructed and operates in substantially the same manner disclosed in the patent referred to, and the presser P , which preferably has 110 a face of yielding material and is constructed and mounted as in the patent referred to, has also a well-known construction and operation.

The labeling device comprises the label-box L , having projecting ribs at its upper end to retain the labels, and fits over the plunger L' , as indicated in Fig. 5. Labels may be inserted in the box through a suitable opening in the side of the same, the label-box 120 being raised upon the plunger for this purpose. The plunger is rigidly secured to the platform L^2 , which is mounted to reciprocate vertically upon the rods or guides A^5 , the platform being provided with suitable guides L^3 , engaging 125 these rods. The label-slide K , which is always positively reciprocated, is mounted upon these rods above the platform, and it is connected with the platform by a suitable compensating gear, which serves to feed the plunger forward at the same rate that the labels 130 are withdrawn from the label-box, so that as

the label-box is reciprocated during the operation of the machine the top label in the box is always pressed against the pasted article in the runway with the same force.

5 The ratchet K' , which is rigidly secured to the worm-gear K^2 , is mounted in the label-slide K . The worm engages the worm-wheel K^3 , which carries on the same shaft the pinion K^4 . The ratchet is fed forward one or more 10 teeth at a time by engaging the pawl K^5 , pivoted to the frame of the machine and pressed into operative position by the spring K^6 . The adjusting-screw K^7 serves to adjust the position of the pawl, so as to regulate the extent 15 through which the ratchet is fed. The rack L^4 is pivoted about the pin L^5 in the platform, and it is normally held in engagement with the pinion K^4 by the lock L^6 , which is preferably pivoted in the platform, the lock being 20 provided with the thumb-nut L^7 on its outer end for operating the same. The lock is also provided with the striker-arm L^8 , which engages the striker L^9 , secured to the slide K , when the platform has been fed forward as 25 far as desired by the compensating gear, and this action rotates the lock L^6 , so as to release the rack L^4 from the pinion K^4 . This allows the platform to drop, so as to carry the label-box out of engagement with the runway, so 30 that when the rack is disengaged from the pinion the label-box is no longer reciprocated, but the link K^8 merely reciprocates the slide. If desired, of course the rack may be positively moved out of engagement with the 35 pinion by a spring or any other desired means. Thereafter when the labels in the box have been replenished the rack is moved into engagement with the pinion, and then the lock is manually brought into engagement with 40 the rack, so as to hold the rack and pinion in engagement during the normal operation of the device. It is of course understood that it is not necessary to employ the exact form of compensating gear which has been 45 described.

The actuating mechanism by which the reciprocating feeder is moved forward to simultaneously feed a series of articles along the runway, then the retainers moved down 50 to clamp these articles in position and to firmly hold them while the intermittently-operating labeling devices act upon them at the several stations, is substantially the same as indicated in the patent referred to, the series of operating-shafts M , N , O , and N^4 being mounted in the frame of the machine to move the various parts. The operating-handle M' is secured to the shaft M , and the arm M^3 is also secured to this shaft, this arm serving to 55 operate the feeder. The shafts N and N^4 are rotated substantially in synchronism with the shaft M by the yoke N^3 , pivoted at M^5 to the arm M^3 and at N^2 to the arm N' , rigidly secured to the shaft N . This shaft through 60 a spring connection operates the presser P . The shaft N^4 operates the spring N^{10} , which

is connected to the link K^8 , which reciprocates the label-slide K . This label-slide is by means of the compensating gear connected to the platform, so that the label-box 70 is in this manner reciprocated during the normal operation of the machine.

Many modifications may be made by those familiar with this art without departing from the spirit of this invention. Parts of this 75 machine may be used without employing all of the same, and parts may be employed in connection with other devices well known in this art. I do not, therefore, wish to be limited to the disclosure which I have made in 80 this case; but

What I claim as new, and what I desire to secure by Letters Patent, is set forth in the appended claims:

1. In a labeling-machine, a runway composed of two longitudinal guides mounted so as to be laterally adjustable, a reciprocating feeder mounted in one of said guides, a connector adjustably mounted on said feeder, a series of spring-pressed feeding-pawls on said 85 feeder, a series of holding-pawls pivoted to said connector, an actuator pivoted to said holding-pawls to simultaneously move them into operation and also to reciprocate said feeder, a gage mounted in said guide adjacent said feeder to regulate the extent of reciprocation of the same, a series of retainers mounted at stations along said runway to clamp articles in position at said stations, said retainers being adjustably mounted in 90 slides by universal joints, retainer-levers operated in unison by a retainer-bar, retainer-links connected to said levers and having a pin-and-slot connection with said slides, springs between said links and said slides and 95 means to operate said retainer-levers comprising an oscillating retainer-arm, a connecting-bar having a pin-and-slot connection with said retainer-arm, a latch pivoted to said retainer-arm and engaging said connecting- 100 bar, a trip to disengage said latch and a spring to quickly disengage said retainers when said latch is released, and intermittently-operating labeling devices co-operating 105 with said runway.

2. In a labeling-machine, laterally-adjustable guides to form a runway, a reciprocating feeder mounted in a guideway in one of said guides to be supported thereby during its reciprocation, a series of feeding-pawls pivoted to said feeder, a connector mounted on said feeder by screws engaging connector-slots in said connector, holding-pawls pivoted in said connector, there being a stop to limit the movement of said holding-pawls, an actuator connected to said holding-pawls to operate the same and to reciprocate said feeder, labeling devices mounted below said runway to co-operate with the same, retainers mounted above said runway to clamp articles to the same 120 while said labeling devices are operating, yielding means to move said retainers into 125

130

engagement with articles, said means comprising a latch and trip to quickly release said retainers from said articles.

3. In a labeling-machine, a runway, labeling devices mounted adjacent said runway, retainer-supports mounted adjacent said runway, slides mounted in said supports, retainers adjustably mounted in said slides with a universal-joint connection, retainer-levers pivoted in said supports, links having a pin-and-slot connection with said slides, springs between said pins and said links, a retainer-bar between said levers and means to actuate said levers comprising a connecting-bar, a retainer-arm having a pin-and-slot connection with said connecting-bar, a spring between said retainer-arm and said connecting-bar, a latch to connect said retainer-arm and connecting-bar and a trip to disengage said latch to allow said spring to quickly release said retainers.

4. In a labeling-machine, a runway, retainers mounted adjacent said runway to clamp articles in position thereon, springs to yieldingly operate said retainers and actuating means for said retainers comprising a spring, a latch and means to release said latch to quickly disengage said retainers.

5. In a labeling-machine, a runway, a series of spring-pressed retainers to clamp articles upon said runway and means to actuate said retainers comprising a spring and latch and means to release said latch to allow said spring to quickly disengage said retainers.

35 6. In a labeling-machine, a runway, a series of spring-pressed retainers to clamp articles upon said runway and means to operate said retainers comprising a latch to quickly disengage said retainers.

40 7. In a labeling-machine, laterally-adjustable guides to form a runway, intermittently-operating labeling devices mounted below said runway to coöperate therewith, a movable retainer-bar, retainers above said runway yieldingly actuated from said retainer-bar to clamp articles upon the runway adjacent said labeling devices, a reciprocating feeder of rectangular cross-section mounted in a rigid guideway in one of said guides to 45 be supported throughout the whole length of said feeder during its reciprocation, a series of feeding-pawls on said feeder and means to reciprocate said feeder.

8. In a labeling-machine, laterally-adjustable guides to form a runway, labeling devices adjacent said runway to coöperate therewith, a reciprocating feeder mounted in a guideway in one of said guides to be supported throughout the whole length of said 55 feeder during its reciprocation, an adjustable gage extending around said guide and adjustable gage-screws in said gage to limit the reciprocation of said feeder.

9. In a labeling-machine, guides to form a

runway, labeling devices mounted adjacent 65 said runway to coöperate therewith, a reciprocating feeder mounted in a guideway in one of said guides to be supported throughout substantially the whole length of said feeder during its reciprocation, a series of feeding-pawls on said feeder, a slotted connector adjustably mounted on said feeder, a series of positively-actuated holding-pawls on said connector and a gage extending around said guide to limit the extent of reciprocation of 75 said feeder.

10. In a labeling-machine, a runway, labeling devices coöoperating with said runway, a spring-pressed retainer to clamp articles upon said runway and means to actuate said retainer comprising a spring and latch and means to release said latch to allow said spring to quickly disengage said retainer.

11. In a labeling-machine, a runway, a spring-pressed retainer to clamp articles upon 80 said runway and means to actuate said retainer comprising a spring and latch and means to release said latch to allow said spring to quickly disengage said retainer.

12. In a labeling-machine, a runway, a spring-pressed retainer to clamp articles upon 85 said runway and means to operate said retainer comprising a latch and releasing means to quickly disengage said retainer.

13. In a labeling-machine, means to support an article to be labeled, a retainer to clamp an article upon said means and means to operate said retainer comprising a latch and releasing means to quickly disengage 95 said retainer.

14. In a labeling-machine, laterally-adjustable guides to form a runway, intermittently-operating labeling devices mounted below said runway to coöperate therewith, retainers to clamp articles upon said runway adjacent said labeling devices, a reciprocating feeder of rectangular cross-section mounted in a rigid guideway in one of said guides and retained in said guideway to be supported throughout the whole length of said feeder 105 during its reciprocation, a gage to adjust the extent of movement of said feeder and a series of spring-pressed feeding-pawls on said feeder.

15. In a labeling-machine, a runway, labeling devices mounted adjacent said runway, retainer-supports mounted adjacent said runway, slides mounted in said supports, retainers adjustably mounted in said slides, retainer-levers pivoted in said supports, links having a yielding connection with said slides and a movable retainer-bar connecting said levers to actuate the same.
